Patented Sept. 9, 1856.

UNITED STATES PATENT OFFICE.

SAMUEL H. GILMAN, OF NEW ORLEANS, LOUISIANA.

IMPROVEMENT IN PANS FOR EVAPORATING SUGAR.

Specification forming part of Letters Patent No. 15,694, dated September 9, 1856.

To all whom it may concern:

Be it known that I, SAMUEL H. GILMAN, of the city of New Orleans, in the parish of Orleans and State of Louisiana, have invented a new and useful improvement in evaporators for evaporating saccharine or other juices and heating water or other liquids by direct heat; and I do hereby declare the following to be a full, clear, and exact description of the same, reference being had to the annexed drawings, which form a part of this specification, and are lettered to correspond therewith.

The object of my invention is to make an evaporator with special reference to its use in making sugar direct from cane-juice, but which may be used for the purpose of evaporating or heating any liquids when the economy of fuel is a prominent object, and to make it economize fuel and improve the quality of the sugar to such an extent and at such a cost for the evaporators as to make its adoption a profitable investment for the smaller as well as the larger class of sugar-planters, and also to make it, in its construction and operation, to conform as nearly as possible to the ordinary train of sugar-kettles, with the management of which every sugar-planter is familiar.

The improvements in the quality of sugar, when made direct from cane-juice, and the economy of fuel in making it, have hitherto been effected by the use of steam, which necessarily requires such expensive and complicated apparatus for its application that only the largest class of sugar-planters can adopt it and only the most skillful mechanics manage it.

The method of making sugar on a large majority of plantations is by the train of from four to seven hemispherical kettles set in masonry, in which they hang by flanges around their tops, with a flue under them, through which the fire passes from the furnace to the chimney, the furnace being under the "battery" or last kettle in the train, and in which the sugar is finished, and the chimney being at the opposite end of train, near the "grande" or first kettle, in which the cane-juice from the mill is received, and from which, after being "limed," clarified, and skimmed, it is passed into the next kettle, in which it is also skimmed, the skimmings being thrown back into the grande, and so on until the juice reaches the battery, each kettle being skimmed

back into the next, each kettle being set a few inches lower than the one preceding it, so that as they "boil over" the foam and skimmings will naturally run into the next kettle back, the battery being the highest and the grande the lowest kettles in the "train." The heating-surface exposed to the fire and hot gases in a train of the above description of the average size is two hundred and fifty-four square feet, and the amount of wood consumed to make sugar in such a train is one and one-half cords an hour, which is equivalent to one cord per hour applied to one hundred and sixty-three square feet of heating-surface. The average amount of sugar made is one thousand pounds of merchantable or drained sugar with four cords of wood weighing two thousand pounds per cord, and the amount of water evaporated to obtain one pound of drained sugar being ninety-three pounds, it follows that one pound of wood evaporates but 1.48 pound of water in the ordinary kettle-train. The proportion of wood consumed per hour to heating-surface in the best constructed steamboat and other furnaces is one cord to one thousand square feet, and the result is three and one-half pounds of water evaporated by one pound of wood, which is a result of 2.36 to one over the kettle-train of Louisiana, and which result is obviously due to the different proportions of heating-surface to fuel. An extension of the proportion of heating-surface to fuel on the plan of the kettle-train described for making sugar to anything like the proportions existing in other methods of applying heat to evaporate liquids is impracticable, from the nature of the cane-juice, which must be heated to the boiling-point as soon after being expressed from the cane as is consistent with the process of clarification and skimming or otherwise cleaning, and the heated gases, after having passed under the length of the ordinary train, are too much reduced in temperature to heat another kettle or body of juice in the required time.

My improvement consists in a comparatively unlimited extension of the heating-surface without exposing any of the kettles or boilers which compose my train or evaporator to the exclusive low temperature of heat corresponding to the length of the flue from the furnace to the chimney. The temperature of the heat applied to each boiler of my evaporator cor-

responds to its or their direct distance from the furnace. The temperature of the heated gases after passing over the length of my evaporator being much too low to produce unaided any useful result or effect upon a body of cane-juice, they are returned on the opposite side of the same thin strata of juice which absorbed their heat and reduced their temperature while passing through the direct flue from the furnace, the high temperature on one side of these strata or columns of cane-juice being indispensable to effect the violent ebullition required in sugar-making, while the lower temperature on the opposite side in the return-flue, being much higher than that of the boiling juice, acts as an auxiliary in keeping up the ebullition. I increase the proportion of square feet of heating-surface to cubic feet of juice contents in each boiler as their distance from the furnace increases, this increase of proportions being necessary to compensate for the decrease of temperature and make the grande and other boilers farthest from the furnace boil faster and more in accordance with the objects sought for than would be the case with the above proportions equal. I also make such an arrangement and disposition of the cane-juice in vertical and horizontal strata as will, by exposing the different strata of the same boiler to different temperatures, produce a rapid circulation and prevent the deposit of feculent or other matter, and by the friction of this circulating current prevent the incrustation on the metal of the evaporators of lime or other substances used in clarification, which substances usually form a coating or scale on the kettles, so as to seriously impede the passage of heat through the metal of which the kettles are made. This rapid circulation also brings all parts of the body of cane-juice periodically into that part of the evaporator which is exposed to the greatest heat. Each one of the boilers composing my evaporator is surrounded at its top by a skimming-trough, for the double purpose of receiving the skimmings and to prevent one boiler from boiling over into another.

Having stated the nature of my improvement in evaporators, I will now proceed to describe the manner in which the evaporator is constructed and operated.

My evaporator is formed by a train or series of open boilers of three or more, four being here shown, Q P O N, as the best number, all standing in contact with and attached to each other in their parts extending above the heating-surface, and with a common battery, R, to finish the sugar in when a steam-battery is not used for that purpose. Each boiler Q P O N, as seen on the "plan," is of a rectangular form, with a skimming-trough, S, around its top. Each boiler has a flat bottom, y, turning up on all sides to a common horizontal plane, N O P Q, and then turning horizontally outward on their sides to the side plates, z, and on their ends vertically

against the division-plates z. Each boiler has a side and bottom "water-leg" or strata, n' o' p' q', of juice, dropping perpendicularly from its bottom on each side at the point where the lower and upper portions of the bottom meet, and turning horizontally inward the two side legs, n' o' p' q', meet below, and thus form the sides and bottom of a canal, which being closed at the top by the bottom of the boiler y, from which the water-leg started, a flue, x, is thus formed entirely surrounded by juice or liquid, as seen at the sections L M, J K, G H, E F; and when the boilers are all set in one train, with their ends in contact, these vertical and horizontal strata n' o' p' q', with the bottoms y of the boilers, form the main central flue, x, and the vertical and horizontal strata n' o' p' q' also form the inside of the two return-flues u u and the top of the bottom return-flue v. Each boiler has one or more central water-legs or juice-strata, n o p q, connecting the main body of the juice above and through the bottom y with the horizontal strata n' o' p' q' below. These central strata divide the main flue x vertically and longitudinally into two or more divisions. The length of these central strata being less than the boiler in which it is made, there is consequently a space between the ends of the central strata of each boiler (in the main flue) x which is not divided. These central strata or water-legs increase in number and decrease in thickness as the distance from the furnace increases, the sirup-boiler Q next to the furnace having one and the grande-boiler N farthest from the furnace having four. The bottom plates of the boilers, y, are placed on a higher level as the distance from the furnace increases, and the depth of juice in each boiler is thus kept proportionate to the temperature in the flue beneath it, while the top level of the contents of all the boilers may be the same. The upper level of the bottoms y, which covers the side return-flues, u u, is in the same horizontal plane in all the boilers. The boilers are attached to each other by division-plates z, which plates form the ends of each boiler and the division between them. The sides z are also attached to and of the same height as the division-plates, and the two connected form the top of each and all the boilers. The skimming-trough S is set on the top of the plate z, which forms the top or sides of all the boilers, and the trough is made entirely around the top of each boiler, and is connected so as to make one common trough, into every part of which the skimmings from either boiler will run, and from which they can be discharged at any desired point; or the trough may be divided and the contents discharged at different points, at the option of the operators.

The evaporator is set in masonry, so as to form a canal or flue, u u, on each side of it, communicating with the back end of the central flue, x, through the evaporator, and with a bottom flue, v, below the horizontal water-leg or strata.

The furnace may be of the ordinary kinds for wood or coal or the furnace patented by me for burning bagasse. The battery R, when a coal or wood furnace is used, should be placed over the fire; but when my patent bagasse-furnace is used it should be placed over the flue between the furnace and evaporator.

Operetion: The train or evaporator being in operation, the heated gases from the furnace pass into and through the central flue, x , to the back end, where the current divides and returns on both sides of the evaporator through the two side flues, u u , to the furnace end of the evaporator, where the two currents pass down and unite in the bottom flue and pass off through it to the chimney after having passed three times the length of the evaporator. The central strata, n o p q , of juice, being in the hottest part of the current of heated gases, will obviously boil the most rapidly, and the current thus constantly ascending through them must be returned through the side and bottom legs, n' o' p' q' , in or around which the temperature is much lower; and in this manner the desired rapid circulation is kept up, and all parts of the body of juice periodically passed up through the central legs and exposed to the greatest heat. The side strata or legs have a temperature differing in degree on their opposite sides as they approach the furnace, where the inside has the temperature of the furnace and the outside the temperature of the gases which have passed twice the length of the evaporator; but no portion or strata of the juice in this boiler next to the furnace is exposed to a low temperature on both sides. The last boiler from the furnace, which is the grande, N , in which the juice is received from the juice-reservoirs, has a temperature nearly equal applied to all parts of it, as it is at the end of the central flue, x , which returns on both sides of it, and thus the even temperature (extensively diffused through the juice) which is so desirable to obtain, a good clarification is obtained. The temperature of the hot gases in the return-flues u , u , and v would not of itself effect any useful result; but in this manner it is absorbed by the lower temperatures of the vertical and horizontal strata n' o' p' q' , and acts as auxiliary to the central flue, x , or its heated contents in keeping the ebullition of the liquid under operation. The cane-juice being received in the grande N is limed and skimmed in the usual manuer of working the grande of the ordinary kettle-train, and is passed into the next kettle or boiler by the ordinary buckets or by a pump, and in the next boiler the juice is skimmed or brushed with a "sword" into the trough and passed into the next boiler, and so on to the last boiler, Q , where it becomes sirup; and if a steam-battery is used it (the sirup) may be drawn from the bottom through a pipe into the tank; but if a steam-battery is not used the sirup may be passed into the battery by a bucket or pump, as before.

The skimming-trough S may be so divided as to run its contents from the grande N , which are of an inferior quality, into one reservoir, and its contents from the other boilers, O P Q , into another reservoir, from each of which the clear juice may be pumped back into the grande or next boiler.

My object in extending the heating-surface to the extent herein shown is to reduce the temperature of the heated gases to the lowest point consistent with an adaquate draft in the chimney, and thereby, by transmitting their heat to the cane-juice, obtain the greatest possible economy of fuel.

My object in increasing the proportion of square feet of heating-surface to cubic contents of juice-space as the distance from the fire increases is threefold; first, to compensate for a lower temperature in the back boilers, and thereby make them boil faster and more in accordance with the object sought for than they otherwise would; second, to diffuse the heating-surface, as the heat decreases more extensively through the body of cane-juice in proportion as it is less clarified, and thereby promote the separation of the feculent and other foreign matters from the juice and cause them to rise to the surface in the process of clarifying and cleaning the juice as it is received into the first boiler, N , and advanced to the others, respectively, as it becomes of a proper density and purity; third, to present to the action of the fire on the central legs, n , o p q , a thicker body or strata of juice in proportion as they approach the furnace where the heat is strongest, and thereby diminish the liability to burn the metal of which the legs are made, or to make that liability equal in all the boilers, a thicker strata being necessary as the heat increases, to prevent the entire body of juice from being thrown out of the leg by the intense heat, and the exposed and unprotected metal thereby injured.

My object in making use of the central legs or strata is threefold, viz: first, to produce a rapid circulation in the manner before described, and thereby prevent the deposit of foreign matters in the water-legs n' o' p' q' and n o p q ; second, to increase the heating-surface to any required extent or proportion by the number of legs in each boiler; third, to diffuse the heat more extensively through the body of juice, as before described.

My object in placing that portion of the bottom plate of the respective boilers which forms the top of the central flue, x , in different horizontal planes is for the purpose of keeping a body of cane-juice on each plate proportionate in depth to the temperature of the heat beneath it, as a depth of juice sufficient to protect the low temperature beneath the plate y of the grande N would be inadequate to protect that of the sirup Q .

My object in making a skimming-trough, S , between and around the top of each boiler is to prevent the juice from being skimmed, brushed, or boiled over from one boiler into

another, and thereby promote the more perfect cleaning of the juice and the production of a better quality of sugar than can be made by the usual method of skimming and brushing one kettle back into another. The juice or sirup after it arrives in the battery R never or seldom requires to be skimmed. I have not shown a trough, S, around the battery K; but it may be made with one, for the purpose of receiving the sirup or sugar in case the battery boils over.

Having stated the nature and scope of my invention, being an improvement in evaporators for the application of direct heat to the evaporation of saccharine or other juices or water, what I claim as my invention, and desire to secure by Letters Patent of the United States, is—

1. An evaporator formed by the combination of a train of open boilers, N O P Q, the boiler Q to receive the first and the boiler N the last fire, and each of the boilers in succession presenting an extent of surface to the fire in the

inverse ratio of the intensity of the fire, as well as of its (the boiler's) cubic capacity, constructed and arranged substantially as described, and for the purposes specified.

2. The construction and use of a flue, X, formed by a series of open boilers, N O P Q, and being, in a series of sections of its length, divided longitudinally and vertically by water-legs or strata of juice into two or more flues or spaces, the number of flues increasing from one section to the next as the distance from the furnace increases, and the number of sections into which it is so divided corresponding to the number of boilers in the series, and each section being shorter than the boiler in which it is placed, so as to leave a space between each section where the flue X is undivided in its transverse section, substantially as described.

SAMUEL H. GILMAN.
